UNITED STATES PATENT OFFICE.

**JAKOB JOHANNESEN LINDANGER, OF SONDRE LINDANGER, SKJOLDESTROMMEN,
NORWAY.**

DESIGN FOR A MEDAL.

51,863.

specification for Design. Patented Mar. 12, 1918.

Application filed August 8, 1917. Serial No. 185,215. Term of patent 14 years.

To all whom it may concern:

Be it known that I, JAKOB JOHANNESEN LINDANGER, a subject of His Majesty the King of Norway, residing at Sondre Lindanger, Skjoldestrommen, Norway, have invented a new and ornamental Design for a Medal, of which the following is a specification, reference being had therein to the accompanying drawing.

The present ornamental design relates to a medal.

It is shown in obverse and reverse in Figures 1 and 2, respectively, of the annexed drawings.

Copies of this patent may be obtained for five cents each, by addressing the "Commissioner of Patents, Washington, D. C."

What I claim and desire to secure by Letters Patent of the United States is:—

The ornamental design for a medal, as shown.

In testimony whereof I have hereunto subscribed my name in the presence of two witnesses.

JAKOB JOHANNESEN LINDANGER.
